DESIGN FOR A TIME RECORDER CASING

Wilbur Henry Adams, Cleveland Heights, Ohio, assignor to Stromberg Electric Company, Chicago, Ill., a corporation of Delaware

Application December 14, 1936, Serial No. 66,518

Term of patent 7 years

To all whom it may concern:

Be it known that I, Wilbur Henry Adams, a citizen of the United States, residing at Cleveland Heights, in the county of Cuyahoga and State of Ohio, have invented a new, original, and ornamental Design for Time Recorder Casings, of which the following is a specification, reference being had to the accompanying drawing, forming a part thereof.

The drawing is a perspective view of a time recorder casing showing my new design.

I claim:

The ornamental design for a time recorder casing, as shown.

WILBUR HENRY ADAMS.
